UNITED STATES PATENT OFFICE

GERHARD DANKER, OF ORADELL, NEW JERSEY, ASSIGNOR TO GRANDOLIER LIGHTING
FIXTURE CO., OF NEW YORK, N. Y.

DESIGN FOR A LIGHTING-FIXTURE BASE OR ARTICLE OF SIMILAR NATURE

Application filed March 3, 1930. Serial No. 34,723. Term of patent $3\frac{1}{2}$ years.

To all whom it may concern:

Be it known that I, GERHARD DANKER, a citizen of Germany, residing in Oradell, in the county of Bergen and State of New Jersey, have invented a new, original, and ornamental Design for a Lighting-Fixture Base, or Article of Similar Nature, of which the following is a specification, reference being had to the accompanying drawing, forming a part thereof.

Figure 1 is a perspective view of a lighting fixture base showing my new design.

Fig. 2 is a front elevational view of the same.

I claim:

The ornamental design for a lighting fixture base, or article of similar nature, as shown.

In testimony whereof I affix my signature.

GERHARD DANKER.
